Karl Packendorf

UNITED STATES PATENT OFFICE

KARL PACKENDORF, OF BERLIN-LICHTERFELDE, GERMANY, ASSIGNOR TO MIX & GENEST AKTIENGESELLSCHAFT, OF BERLIN-SCHONEBERG, GERMANY, A COMPANY OF GERMANY

PNEUMATIC-DISPATCH SYSTEM

Application filed April 26, 1928, Serial No. 273,104, and in Germany May 6, 1927.

This invention concerns improvements in or relating to pneumatic tube conveying or delivering systems such as are commonly employed, *inter alia*, for postal purposes and 5 has as its object to increase the capacity and usefulness of such systems by enabling a single tube-line to be employed for simultaneous traffic in both directions.

To this end according to the present invention a tube line is provided with one or more switch tubes or by-pass tubes with the aid of which objects conveyed or delivered, such as containers for postal packets, may be carried past one another in opposite directions; this makes it possible to use the line 15 for simultaneous two way traffic.

One embodiment of the invention is illustrated diagrammatically and by way of example in the accompanying drawing which 20 shows a passing point in a tube line of a pneumatic system.

In the drawing *a* and *c* indicate the ends of two sections of main pneumatic tube line. The length of tube *a* discharges through a 25 switch or by pass tube *b* into the length *c* and the latter discharges through a similar tube *d* into said length *a*. There is an opening *e* at the connection between the tubes *a*, *b* and an opening *f* at that between the tubes 30 *c*, *d*. These openings may be provided in the tube walls or may take the form of interruptions separating the tube walls from one another. Between the point of forking *g* and the opening *e* the section *a* of main tube line 35 contains a flap valve *h* and a contact device *i*. The switch *b* is provided with a contact device *k* and a flap valve *l*. The section *c* of main tube line is furnished with a flap valve *n* and a contact device *o* between its point of 40 forking *m* and the opening *f* while the switch tube *d* contains a contact device *p* and a flap valve *q*. The position of the stops *r* shown indicates diagrammatically in which direction the flap valves *h*, *n*, *l*, *q* are respectively 45 capable of moving in the tubes.

The contact devices *i*, *p* control the operating fluid in the section of tube line *a* by, for example, regulating the action of a blower associated therewith while the contact devices 50 *o*, *k* similarly control the operation of a blow-

er acting on the section of main tube line *c*. The blowing arrangements being well known will not be described or illustrated in the present specification.

An arrow *s* indicates the direction of action 55 of the operating fluid, namely compressed air, in the section of tube line *a* and an arrow *t* the direction thereof in the section of tube line *c*.

Objects such as containers for postal packages approaching one another in opposite directions along the sections of tube *a*, *c* pass the 60 openings *e*, *f* into the switch tubes *b*, *d*. The flap valves *q*, *l* are kept closed by the compressed air acting thereon from the tube sections *a*, *c* respectively so that no obstacle is 65 presented to the entry of the containers into said switch tubes *b*, *d*. By means of the contact devices *i*, *o* which are actuated by the containers in passing, the blowers are momentarily set out of operation after which they are set in operation once more by the containers traversing the further contact devices *k*, *p*; said blowers are, however, now arranged 70 to exert a suction action on the main tube sections *a*, *c* by, for example, rotating the said blowers in the opposite direction. The flap valves *l*, *q* open automatically under the pressure of the outside air acting on the tubes *b*, *d* 75 through the openings *e*, *f*. The containers located in said switch tubes *b*, *d* are therefore conveyed into the sections of main tube line *c*, *a* respectively where they continue their course. The suction in these line sections 80 maintains the flap valves *n*, *h* closed so that 85 said suction can only act over the paths *e*, *b*, *c* and *f*, *d*, *a* but not directly over *f*, *c* or *e*, *a* and thus exerts its full power in the tubes *b*, *d*.

A carrier that under the action of the compressed air has passed beyond the flap valve 90 *h* or *n* cannot be returned to the station whence it arrives, because the suction then produced will close the flap valves *h*, *n* and thus prevent the suction from acting in the tube portions *h*—*e* or *n*—*f*. These portions can be made so 95 long that it shall be sufficient to insert the carriers about the same time, or nearly so, if the tubes *b*, *d* are located in the middle of the transit tube. Or the tube sections *a*, *c* may 100 each contain an arresting device, these devices

being equidistant from the tubes *b*, *d* are not only getting retracted from their operative position if both are acted upon by each a carrier or a series of carriers. In this way it can be avoided that the carriers must be dispatched simultaneously or at a proper time. Such arresting devices are not shown since not being necessary to perform the invention.

What is claimed is:

10. 1. In a pneumatic dispatch system, a single tube line consisting of two sections, and two tubes which interconnect these sections to enable conveyance to take place in both directions simultaneously.
15. 2. In a pneumatic dispatch system, a single tube line consisting of two sections, two tubes interconnecting these sections, and means for reversing the direction in which the propelling air is moving.
20. 3. In a pneumatic dispatch system, a single tube line consisting of two sections, two tubes interconnecting these sections, means for reversing the direction of travel of the propelling air, and means for closing the said 25 interconnecting tubes against the tube sections to which they respectively deliver, these means being efficient until the reversal of the air action.
25. 4. In a pneumatic dispatch system, a single tube line consisting of two sections, two tubes interconnecting these sections, means for reversing the direction of travel of the propelling air, such means governed by the carriers, and means for closing the said interconnecting 30 tubes against the tube sections to which they respectively deliver, these means being efficient until the reversal of the air action.
35. 5. In a pneumatic dispatch system, a single tube line consisting of two sections, two tubes interconnecting these sections, air passages being provided between either of these sections and the interconnecting tube forming the continuation thereof, and means for reversing the direction of travel of the propelling air.
40. 6. In a pneumatic dispatch system, a single tube line consisting of two sections, two tubes interconnecting these sections, means for reversing the direction of travel of the propelling air, and means for closing, on the reversal 45 of the air flow, each of the said sections against the interconnecting tube forming the continuation thereof.

KARL PACKENDORF.
